UNITED STATES PATENT OFFICE.

ALBERT ANDERSEN, OF CHICAGO, ILLINOIS, ASSIGNOR TO AUTOMATIC ELECTRIC COMPANY, OF CHICAGO, ILLINOIS, A CORPORATION OF ILLINOIS.

CALL-SENDING DEVICE.

1,391,442.

Specification of Letters Patent. Patented Sept. 20, 1921.

Application filed August 8, 1914. Serial No. 855,826.

To all whom it may concern:

Be it known that I, ALBERT ANDERSEN, a citizen of the United States of America, and resident of Chicago, Cook county, Illinois, have invented certain new and useful Improvements in Call-Sending Devices, of which the following is a specification.

My invention relates to improvements in call-sending devices and consists in the provision of a plurality of impulse transmitters controlled by a single keyboard.

My invention is particularly adapted for use in connection with automatic telephone systems in which the called subscriber's number consists of a plurality of digits, and in accordance with my invention I provide as many impulse transmitters as there are digits in the called number. I then provide a single keyboard under the control of the operator and mechanism whereby the operation of the various keys of this board will successively bring the impulse transmitters into operation.

My invention will be more clearly understood by reference to the accompanying drawings, in which I have illustrated one particular embodiment of my invention.

In the drawings Figure 1 represents a front side view of a call-sending device embodying the features of my invention, showing certain parts removed so as to more clearly show the interior construction.

Fig. 2 is a back view of a portion of the same.

Fig. 3 is a sectional view taken on the line 3—3 in Fig. 2.

Fig. 4 represents the top of a portion of the keyboard associated with the call-sending device shown in Figs. 1, 2 and 3.

Fig. 5 is a side view of the same, showing the springs controlled by each push button or key.

Fig. 6 is a bottom view of said keyboard.

Fig. 7 is a diagrammatic circuit view of the keyboard and the call-sending device.

Referring to Figs. 1, 2 and 3, the call-sending device shown consists of three units or impulse transmitters X, Y and Z—that is, one for each digit of the number to be called—but it is readily seen that any number of units or impulse transmitters may be grouped together to form one call-sending

device, depending upon the number of digits in the called number.

Referring to the unit X, among other details, are a plurality of solenoids a' , a^2 , a^3 , etc., circularly mounted between the plates C and D. Each solenoid is provided with a plunger 11 which, when attracted, protrudes through the plate D in the path of the arm 12. The second calling device Y is shown with the plate C removed, illustrating the holes in the plate D through which the plungers of the solenoids a' , a^2 , etc., protrude when attracted. The third calling device Z is illustrated with both the plates C and D removed, showing a third plate P through which projects a shaft 20. To the end of said shaft is secured a disk 15 and the arm 12. These devices are mounted alongside each other on the base plate 10. Fig. 2 shows the assembly of one of the calling devices at the back of said base plate, together with a solenoid 16 which, when energized, attracts its plunger 17 and by means of a link 18 operates the lever 19 against the tension of the spring 21. On the end of the lever 19 is the segment of a gear wheel 22 in mesh with a gear wheel 23. The said gear wheel is secured to the shaft 20, which is journaled at one end in the plate P and at the other end in the bridge piece 25. To the under side of the disk 15 is secured a pawl 26, its function being to engage with the ratchet wheel 27 which is attached to the gear wheel 28. This gear wheel is loosely mounted on the shaft and is in mesh with a smaller gear wheel 29 which is on the same shaft as the impulse cam 30 and the wheel 31. The wheel 31 meshes with the worm 90 connected with the governor 32. With each of the units or transmitters (excepting the first) is associated a slow acting relay 35 mounted on the rear of said transmitter. Each of these relays is provided with an armature 37 and spring 38, the end of which latter is turned up in such a manner as to arrest the revolving of the governor 32 when the magnet 35 is energized. This is accomplished by the end of the spring 38 coming into the path of the pin 39 which passes through the shaft of the governor. Associated with each transmitter is a pair of springs 40 fastened to the base plate by

means of a bracket 41 and insulated from each other and from the frame by suitable insulating material.

Associated with the keyboard and with the unit or transmitter No. 1 (Fig. 7) is a group of inter-related relays. The relay 43 controls the contacts of the pairs of springs 44 and 45 and the operation of the retaining pawl 54. The retaining pawl 54, when in its normal position, prevents the shaft 55 from rotating. Attached to one end of the armature 48 of the relay 47 is a locking spring 56, the function of which is to lock the armature 46 of the relay 43 in an operated position after the relay 43 has once operated and releases the same when the said relay 47 is energized. Attached to the opposite end of the armature 48 is a retaining pawl 49 which engages the teeth of a ratchet wheel 50, which latter operates to retain the said ratchet wheel in an operated position. Attached to the armature 52 of the relay 53 is a driving pawl 58, the function of which is to rotate the ratchet wheel 50 step by step over the contact points 51. This causes the wiper 59 to supply battery current to the various units through its contact points 51 as the said wiper is rotated over them step by step.

Referring to Figs. 4, 5 and 6, there is there illustrated a section of the keyboard, together with the assembly of the contact springs to close the necessary circuits to initiate a call. Fig. 6 is a view of the under side of the keyboard, showing the contact springs 60, which are in a group of three. The ends of these springs are shown in Fig. 5 and are pressed together when their corresponding key 61 is depressed. The springs 62 and 63 are closed by the depression of any one of the keys 61 in the following manner: Upon the depression of one of the keys 61 a projection 64 attached to said key is forced between two of the steel balls 65, forcing them apart and acting on a lever 66, which in turn forces together the springs 62 and 63. These springs remain in their operated position by means of a detent arrangement on the end of the spring 67 until the start key 68 is depressed, when it moves said spring 67 out of engagement with the lever 66, which lever releases and allows the contact springs 62 and 63 to be separated. At the same time the start key 68 closes the circuit of the relay 43 (Fig. 7) by pressing together the contact springs 69 and 70.

This series of operations is performed in the following manner: The lever 66 is pivoted to a support 66^a which is fastened to the frame. One end of this lever is provided with a lug which extends into the path of the pin which is controlled by the steel balls and a bushing which presses 65 against the spring 62. The other end of

this lever is adapted when rotated about its axis to fall behind the detent on the end of the spring 67 to hold it in its operated position. The start key 68 is located back of the support 66^a and is provided with an insulated washer which normally rests against the frame and when the key is pressed forces the springs 69 and 70 into contact. The lower end of this key when pressed passes over an opening in the bridge 68^a and engages the detent on the end of the spring 67 to release said spring from engagement with the lever 66 and to allow the lever 66 to be restored to its normal position by the tension of the spring 62.

Having given a detailed description of the component parts, I will now describe the mechanical and electrical operations which take place when a call is initiated, referring more particularly to the diagrammatic view shown in Fig. 7. As hereinbefore stated, there is mounted on the base plate a plurality of units or transmitting devices. There are as many of these devices as there are digits in the telephone numbers in the system in which the apparatus is used. As shown in the diagrammatic view Fig. 7, the ratchet wheel 50 is arranged to take care of a five digit number, while only three units or transmitting devices are shown.

We will assume that the operator wishes to call a subscriber whose number is 45678. She therefore depresses the keys 4, 5, 6, 7 and 8 in quick succession, which return to their normal positions immediately upon the removal of her finger by the tension of the springs 60, which are momentarily pressed together. Upon the digit key 4 being depressed, three circuits are closed, one through the solenoids a^4 and 16 (associated with the first unit) from ground G' through the springs of the key 4, solenoid a^4 , solenoid 16, contact 51 (associated with the first unit) and the wiper 59 to the battery B. The second circuit extends from ground G' through the same springs to the magnet 53. The third circuit extends from ground G' through the springs 63 and 62 and the supervisory lamp 72 to battery B. The latter circuit is a supervisory circuit and is to indicate that one or more of the calling keys have been depressed, but not the start key, for we have already seen that when the start key 68 is depressed the contact springs 62 and 63 are released. Upon the energization of the solenoids a^4 and 16, the shaft 20 is revolved until it is stopped by the arm 12 coming into contact with the plunger of the solenoid a^4 , whereby the ratchet 26 will be advanced past a number of notches in the wheel 27 corresponding to the digit 4. The relay 53, upon energizing, places the pawl 58 in a position to rotate the ratchet wheel one step as soon as its circuit is broken and it de-energizes. The pawl 54 retains the unit 1

in its operated position. Upon the key 5 being depressed, it closes the contact of springs 60 associated with it in the same manner as the key 4. The operations of the 5 solenoids a^5 and 16 and the apparatus of the second unit or impulse transmitter are the same as for the apparatus of the first unit. Upon the depression of the keys 6, 7 and 8, the individual units or impulse transmitters 10 will respond in the same manner as above described.

As soon as the solenoid of the unit 1 is energized, a circuit is closed through the relay 35 of the second unit, thereby causing 15 the said relay to energize and prevent the operation of unit No. 2 before unit No. 1 has operated. This circuit extends from ground G^s through the said relay 35 and the springs 40 to battery B. The above is 20 true of each succeeding unit, except the last unit of the series, which operates to open its springs 40, thus preventing the circuit of the relay 47 from being closed when the relay 43 is energized at the time the start key is 25 depressed.

The operator now presses the start key 68, which causes the start relay 43 to energize and mechanically unlock the springs 62 and 30 63 which control the supervisory lamp 72. The circuit for the relay 43 extends from ground G' through the contact of springs 69 and 70 and the said relay 43 to battery B. The relay 43, upon energizing, locks its armature 46 under the spring 56 of the armature 48, and operates to release the shaft 55 35 of the first unit by withdrawing the retaining pawl 54 and also closes a circuit through the start supervisory lamp 73. This latter circuit extends from ground G' through the said lamp and the springs 45 to battery B.

As soon as the pawl 54 is removed from engagement with the wheel 29, the spring 21 operates to restore the plunger of the solenoid 16 of the first unit to normal. As the 45 plunger returns to normal, the ratchet 26 engages with the notch in the ratchet wheel 27, to which said ratchet has advanced by the energization of the solenoid, and forces the wheel 27 to rotate back with the shaft 50 20. Through the medium of the spur teeth 28 and the pinion 29 this rotation is transmitted to the shaft 55 on which is fastened the impulse cam 30. The cam 30 revolves 25 to open and close the impulse springs 79 and 80 four times, thereby transmitting that number of impulses over the line conductors 74 and 75 leading to the central office apparatus. As soon as the solenoid 16 of unit 55 No. 1 returns to normal its springs 40 are opened, thereby opening the circuit of the relay 35 of the second unit. The relay 35 being slow to energize allows the central office apparatus time to operate before the second unit is set in motion to transmit the 60 second series of impulses. This second unit

operates to then open the circuit of the relay 35 of the third unit after it has transmitted the second series of impulses, etc., until the solenoid 16 of the last unit deenergizes, whereby the circuit of the release 70 relay 47 is closed. This circuit extends from ground G^s through the said relay, contact of springs 44 and the springs 40 of the last unit to battery B. The relay 47, upon energizing, removes the pawl 49 from engagement with the ratchet wheel 50 for a long enough time to allow the said ratchet wheel to return to normal and unlocks the relay 43, which, upon releasing its armature, opens the circuit of the start supervisory 80 lamp 73 at the springs 45 and opens the circuit of the relay 47 at the springs 44. The extinguishing of the lamp 73 notifies the operator that the calling device may now be used to establish another call. 85

The impulses transmitted by each unit are at a uniform rate of speed, as the governor 32 controls the direct operation of the shaft 55 upon which the impulse cam 30 is mounted. The time interval between the impulses 90 for each digit is controlled by the different relays 35 in such a manner that it is impossible for more than one unit to transmit impulses at one time.

It will thus be seen that I have devised a 95 very efficient form of call-sending device which consists of a plurality of impulse transmitters but of only one keyboard. The impulses transmitted over the trunk line to the switches in the automatic telephone exchange are at a uniform speed and are properly spaced apart so as to secure the proper operation of the automatic switches with which this call-sending device will be associated. 100

While I have illustrated and described one embodiment of my invention, it is to be understood that I do not wish to be limited to the exact construction shown and described. 105

What I claim as my invention is:—

1. A call-sending device comprising a plurality of impulse transmitters, a single controlling mechanism for successively controlling the operation of said transmitters, said transmitters operating thereafter to transmit impulses. 115

2. In a call-sending device, a plurality of impulse transmitters, a single keyboard for successively operating said transmitters, said transmitters operating automatically to transmit impulses after all are operated by said keyboard. 120

3. In a call-sending device, a plurality of impulse transmitters, a plurality of keys under the control of the operator, means for successively bringing said impulse transmitters under the control of said keys, means controlled by the operation of said keys for setting said impulse transmitters in operated 125 130

- position, and means for then successively operating said transmitters to transmit a plurality of series of impulses.
4. In a call-sending device, a plurality of impulse transmitters, a set of operating keys, a side switch, and means controlled by said side switch for successively bringing said impulse transmitters under the control of said keys.
5. In a call-sending device, a plurality of impulse transmitters, a plurality of operating keys, a side switch, means controlled by said side switch for successively bringing said impulse transmitters under the control of said keys, means controlled by said keys for setting said transmitters in operative position, means for then successively operating said impulse transmitters, and means for locking the second transmitter until the first one has completed its operation.
6. In a call-sending device, a plurality of impulse transmitters, means for setting said transmitters in operative position, means for then successively operating said transmitters, a signal lamp operated while said transmitters are being set, and a second signal lamp operated while the impulses are being transmitted.
7. In a controlling apparatus, the combination with a plurality of impulse transmitters, of a group of setting keys common to said transmitters, and means whereby said transmitters may be separately set through successive operations of any one of said keys, each transmitter maintained in set position until all are set.
8. In a controlling apparatus, the combination with a plurality of impulse transmitters, of a group of setting keys common to said transmitters, means operated upon a first actuation of any one of said keys for setting a first one of said transmitters, and means operated upon a second actuation of the same or another key for setting a second one of said transmitters, before the first transmitter has operated to send impulses.
9. In a controlling apparatus, the combination with a plurality of impulse transmitters, of a group of setting keys common to said transmitters, each key corresponding to a particular digit, and a plurality of means operated in turn upon successive actuations of said keys for separately setting said transmitters in accordance with the digits indicated by the actuated keys, said transmitters operating to send impulses only after all have been set.
10. In a controlling apparatus, the combination with a plurality of impulse transmitters, of a group of setting keys common to said transmitters, a setting means for each transmitter, all of said means normally inoperative except the first one, and a device whereby upon successive actuations of said keys said setting means are successively rendered operative, said transmitters operating after being set to transmit impulses.
11. In a controlling apparatus, the combination with a plurality of impulse transmitters, of a plurality of setting means, one for each transmitter, a group of setting keys normally adapted to control a first one of said setting means, and a device whereby after the actuation of one of said keys the control is shifted to another setting means, said transmitters operating after being set to transmit impulses.
12. In combination, a circuit, a plurality of serially related contact sets for controlling said circuit, an electro-magnetic device associated with each contact set for operating the same, and a group of controlling keys common to said devices.
13. In combination, a circuit, a plurality of serially related contact sets for controlling said circuit, an electro-magnetic device associated with each contact set for operating the same, a group of controlling keys common to said devices, and an automatic switching mechanism whereby said devices may be controlled successively through the medium of said keys.
14. In a call sending device, a plurality of impulse transmitters, a common group of setting keys and mechanism controlled thereby for setting said transmitters one after the other, locking means for each transmitter, all of said means normally inoperative except the one associated with the first transmitter, and means whereby each transmitter when set renders the locking means associated with the next transmitter effective.
15. In a call sending device, a plurality of impulse transmitters, a common group of setting keys and mechanism controlled thereby for setting said transmitters one after the other, locking means for each transmitter, all of said means normally inoperative except the one associated with the first transmitter, means whereby each transmitter when set renders the locking means associated with the next transmitter effective, and means controlled by a manual key for unlocking the said first transmitter.
16. In a call sending device, a plurality of impulse transmitters, a group of setting keys common to said transmitters, means whereby said transmitters may be separately set by successive operations of one or more of said keys, means for locking each transmitter in set position, and means for unlocking the transmitters to permit them to send impulses.
17. In a call sending device, a plurality of impulse transmitters, a group of setting keys common to said transmitters, means whereby said transmitters may be separately set by successive operations of one or more of said keys, means for locking each transmitter in

set position, and means controlled by a manual key for unlocking a first one of said transmitters to permit the same to operate.

18. In a call sending device, a plurality of impulse transmitters, a group of setting keys common to said transmitters, means whereby said transmitters may be separately set by successive operations of one or more of said keys, means for locking each transmitter in set position, means controlled by a manual key for unlocking a first one of said transmitters to permit the same to operate, and means controlled by each transmitter after its operation for unlocking the next.

19. In a call sending device, a plurality of locking impulse transmitters, a common group of setting keys and mechanism controlled thereby for setting said transmitters separately, and means for unlocking the first one of said transmitters whereby it may perform its impulse sending function while returning to normal.

20. In a call sending device, a plurality of locking impulse transmitters, a common group of setting keys and mechanism controlled thereby for setting said transmitters separately, means for unlocking the first one of said transmitters whereby it may perform its impulse sending function while returning to normal, and means controlled by each transmitter except the last whereby upon its return to normal the next transmitter is unlocked.

21. In a call sending device, a plurality of locking impulse transmitters, a common group of setting keys, mechanism including an automatic switch controlled by said keys for setting said transmitters one after the other, means for unlocking a first one of said transmitters whereby it may perform its impulse sending function while returning to normal, separate means controlled by each transmitter except the last whereby upon its return to normal the next transmitter is unlocked, and means controlled by the last transmitter for releasing said automatic switch.

22. In a call sending device, a plurality of impulse transmitters, setting means for each transmitter, and a plurality of magnets for each setting means for regulating the setting operation thereof, a single set of keys for controlling the setting mechanism of all the transmitters, said transmitters operating after being set to transmit impulses.

23. In a call sending device, a plurality of impulse transmitters, setting means for each transmitter variably operable to set its associated transmitter in accordance with any one of a plurality of digits, and a plurality of magnets associated with each setting means to control the variable operation thereof, each magnet corresponding to a particular digit, a single set of keys for controlling the setting mechanism of all the

transmitters, said transmitters operating after being set to transmit impulses.

24. In a call sending device, a plurality of impulse transmitters, setting means for each transmitter, a plurality of magnets for each setting means for regulating the setting operation thereof, and a group of controlling keys common to all of said magnets.

25. In a call sending device, a plurality of impulse transmitters, setting means for each transmitter variably operable to set its associated transmitter in accordance with any one of a plurality of digits, a plurality of magnets associated with each setting means to control the variable operation thereof, each magnet corresponding to a particular digit, and a group of controlling keys common to all of said magnets.

26. In a call sending device, a plurality of impulse transmitters, setting means for each transmitter, a plurality of magnets for each setting means for regulating the setting operation thereof, a group of controlling keys common to all of said magnets, and a switching device for shifting the control of said keys from one plurality of magnets to another.

27. In a call sending device, a plurality of impulse transmitters, setting means for each transmitter variably operable to set its associated transmitter in accordance with any one of a plurality of digits, a plurality of magnets associated with each setting means to control the variable operation thereof, each magnet corresponding to a particular digit, a group of controlling keys common to all of said magnets, and a switching device for shifting the control of said keys from one plurality of magnets to another.

28. In a telephone system, a sender comprising a plurality of controlling devices, a single set of digits keys, means responsive to the successive operation of keys of said set for causing said controlling devices to assume set positions corresponding to the keys depressed, and a series of mechanical switches governed in their operations by the subsequent movement of said controlling devices.

29. In a telephone system, a sender comprising a plurality of controlling devices, a single set of digits keys, a progression switch for associating said set with successive controlling devices upon the repeated actuation of said key set, and a series of mechanical switches governed in their operations by the subsequent movement of said controlling devices.

30. In a call sending device, a plurality of impulse transmitters, a single set of keys for setting said transmitters, and means for preventing the sending of impulses thereby until all of the transmitters are set.

31. In a call sending device, a plurality of

105

110

115

120

125

130

impulse transmitters, a single set of keys for setting said transmitters, and means for preventing the sending of impulses thereby until all of the transmitters are set, and 5 means controlled after the last transmitter is set for rendering said last means ineffective.

32. In a call sending device, a plurality of impulse transmitters, a single set of keys 10 for setting said transmitters, and means for preventing the sending of impulses thereby until all of the transmitters are set, a signal associated with said keys, means controlled by the operation of one of said keys for displaying said signal, another signal associated 15 with said transmitters, and controlled by the final operation thereof for displaying said other signal.

33. In a call sending device, a plurality 20 of impulse transmitters, a single set of keys for setting and locking said transmitters, a lamp associated with said keys, means controlled by any one of said keys for lighting said lamp, a manual key, means controlled 25 by said manual key for unlocking a first one of said transmitters to permit the same to operate, and means controlled by each transmitter after its operation for unlocking the next, a lamp associated with said transmitters, and lighted by the final operation 30 thereof.

34. In a call sending device, a visible signal, a plurality of impulse transmitters, means for setting said transmitters, means 35 for preventing the sending of impulses thereby until all of the transmitters have been set, means controlled by the setting of one transmitter for displaying said signal, and means controlled by the release of the 40 first of said transmitters for sending impulses, and for extinguishing said signal.

35. In a call sending device, a visible signal, a plurality of impulse transmitters, means for setting said transmitters, means 45 for preventing the sending of impulses thereby until all of the transmitters have been set, additional means controlled by the

last of said transmitters and effective upon the said last transmitter's return to normal for displaying said signal. 50

36. In a call sending device, signal lamps, impulse transmitters, a set of keys for setting and locking said transmitters, means for lighting one of said lamps upon setting one of said transmitters, a manual key, means 55 controlled by said manual key for unlocking a first one of said transmitters to permit the same to operate to send impulses, and to extinguish said lamp, means controlled by each transmitter after its operation for unlocking the next, and means for lighting another of said lamps after the operation of the last of said transmitters. 60

37. In a telephone system, a sender comprising a plurality of controlling devices, a 65 single set of digits keys, a progression switch, and means responsive to the actuation of a key for causing a controlling device to assume a set position corresponding to the key actuated, for operating said progression switch to operatively associate said key with the succeeding controlling device, and a series of mechanical switches governed 70 in their operations by the subsequent movement of said controlling devices. 75

38. In a telephone system, a sender comprising a series of controlling devices, a single set of digits keys, a progression switch, means whereby each time a key of said set is actuated, a controlling device will be caused to assume a set position corresponding to the key and said progression switch will be moved to shift said key set to operative relation to the succeeding controlling device, and a series of mechanical 85 switches governed in their operations by the subsequent movement of said controlling devices. 80

Signed by me at Chicago, Cook county, Illinois, this 27th day of July, 1914.

ALBERT ANDERSEN.
